United States Patent Office.

JOHN STOCK AND JACOB STOCK, OF NEW YORK, N. Y.

Letters Patent No. 77,548, dated May 5, 1868.

IMPROVED BARBER'S CHAIR.

The Schedule referred to in these Letters Patent and making part of the same.

TO ALL WHOM IT MAY CONCERN:

Be it known that we, JOHN STOCK and JACOB STOCK, of New York, in the county and State of New York, have invented a new and useful "Barber's Chair," and we do hereby declare that the following is a full and exact description of the same, reference being had to the accompanying drawings, and to the letters of reference marked thereon.

The nature of this invention consists in the arrangement of making the back of the chair in two parts, the lower part of which is stationary, while the upper part is hinged on, and is made movable, and provided with a suitable rack to place and fix this said upper part in any desirable and most convenient position.

In the accompanying drawings—

Figure I represents our improved chair with the upper part of the back moved upwards, and

Figure II shows the same closed.

A represents an arm-chair, having the back, B, and the arms C C made of even height. Upon this back, B, a second back, D, is fitted, hinged upon the arms at *n* *n*, capable of being moved upwards into any desired position. To this movable back D, a rack, *m*, is hinged, in the teeth of which a pin or projection fast in the bracket F, and attached to the stationary back, B, is made to work. Against the back of this rack *m* a spring, *x*, is made to work in such a manner as to keep this rack against the projection in the bracket F, at any position the same may be placed.

E is the head-rest, jointed to the bracket *w*, and provided with a segment-rack, *v*, to regulate the position of said head-rest, while the raising or lowering of the same is effected by sliding the bracket *w* upwards or downwards in a suitable socket, *a*, fast to the stationary back B, and is fixed in any desired position by the screw and nut *h*.

What we claim as our invention, and desire to secure by Letters Patent, is—

The movable back D, hinged to the stationary back B of a barber's chair, arranged with suitable mechanism to fix this movable back D in any desired position, in the manner and for the purpose substantially as set forth.

JOHN STOCK,
JACOB STOCK.
